HEATING APPARATUS

Creno P. Bettenga, Marshalltown, Iowa, assignor
to Advance-Marshall Company, Marshall-
town, Iowa, a corporation of Iowa

Application November 9, 1929. Serial No. 406,068

11 Claims. (Cl. 126—93)

The principal object of this invention is to provide a heating apparatus that returns hot gases, unutilized products of combustion and warm air from the outlet pipe of the burner to the inlet pipe of the burner.

A further object of this invention is to provide a heating apparatus that is so arranged as to warm the fuel oil before its moment of ignition.

A still further object of this invention is to provide a heating apparatus that is economical in manufacture, durable in use, and efficient in operation.

These objects I have achieved successfully in actual practice, and by the means which are hereinafter described and claimed, and which are illustrated in one exemplification in the accompanying drawing, which is a side elevation, in perspective and with parts broken away, of a hover for chickens including in the heating means my improved superheater coil.

It is to be understood that minor modifications of this invention are within the scope of the appended claims, and that the return coil of the device exemplified may be incorporated in any species of heating apparatus to which it will be applied where fuel is burned and the partially combined gases of combustion passed through the coil.

In the drawing, the numeral 1 denotes a pair of angular legs adapted to be mounted fixedly upon any suitable supporting base, and having top rings 2 encircling and secured to the pair of vertically erect receiving and delivery end members 5 and 6 respectively of horizontally disposed parts of a convoluted intermediate tube or pipe 3. A hover cover 4 is shown mounted also on said legs above the convoluted pipe part 3 and traversed by said members thereof 5 and 6.

The numeral 8 denotes an elongated rectangular or oblong housing containing a similarly shaped reservoir 19 for liquid fuel. At the rear the top and bottom of said housing has vertically aligned apertures at 10 and 9, the aperture 10 also the aperture 9 being traversed by the longer member 6 of said pipe, the member fitting the upper aperture 10 but being of less diameter than the lower aperture 9. At the front part of the bottom of the housing is provided a fitting aperture for the upper termination of the erect forward pipe member 5, whereby the open top of the inlet pipe 5 communicates with the front inside of the housing 8.

The forward part of said housing has a low transverse front wall 11. A bar 16, hooked at the top is suspended removably in the open top tube 5 and carries at its lower end an open cup 14 having a central depending leg 15 to support it in spaced relation on the bottom coil end. An apertured dropper concaved plate 23 secured adjustably by a screw 24 on the bar 16

receives liquid fuel from a spigot 20 of a tank 19, to deliver it in fine drops into the lower cup 14.

The open front of the housing has its sides 12 sloped downwardly and has a hinged cover 13 with hasp to engage a pin 18 on the wall 11. The tank 19 has the spigot 20 governed by a valve 21, with nozzle 22 to deliver fuel upon the plate 23.

The structures thus described are substantially those shown in my pending application for Patent Serial No. 357,133, filed April 22, 1929.

My principal improvement over said application consists in supplying an inclined cross tube 7 from the rear tube or riser 6 immediately below the housing 8 and to the forward riser tube 5 a little above its connection with the coil and also above the fuel cup 14. The tube 7 is shown of less diameter than the risers but may be of the same diameter.

The operation of the device is as follows: Open the valve of the spigot 20 to permit liquid fuel from the supply tank 19 to fall downwardly in the vertical inlet pipe 5. This liquid will strike the member 23 and be delivered in fine drops to the cup 14. After igniting the fuel, the lid 13 should be closed. With the apparatus in operation fresh air will enter the housing 8 between the outline of the aperture 9 and the outlet pipe 6. This air by coming in contact with the outside of the outlet pipe 6, which extends through the housing 8, will become heated and as it passes rearwardly in the housing 8 to enter the inlet pipe 5, it will not only furnish warm air for the proper burning of the fuel oil, but will warm the fuel oil in the supply tank 19. The convoluted part 3 of the device should be of sufficient length to provide efficient combustion of the fuel oil before the gases from the same pass into the outlet pipe or flue 6. However, as is well known, many valuable heat units in the form of fuel do escape from the outlet pipe of an oil burner and to care for these otherwise lost products of combustion, I have provided the cross pipe 7. This pipe 7 draws off the escaping products of combustion, hot air and gases from the pipe 6 and returns the same to the inlet pipe 5 at a point above the combustion point of the apparatus.

This flow of valuable elements through the pipe 7 is caused by the suction in the pipe 5 as distinguished from the lack of suction in the pipe 6. This suction in the pipe 5 is caused by the downward flow of the fuel oil and air in the pipe 5. Also it will be appreciated that the air and gases in the pipe 6 will be expanded and light relative to weight. The returned hot gases, through the cross pipe 7, will also aid in heating and gasifying the fuel oil.

Although the cross pipe 7 may be inclined, as shown in the drawing, I especially recommend

it for efficient results. The cup 14 and member 23 may be easily removed from the pipe 5 and replaced as easily.

Having described my invention, what I claim 5 as new, and desire to secure by Letters Patent, is:

1. A device of the character described, comprising a tube having an intermediate part with end risers and having a cross connecting tube from one riser to the other, a fuel bowl within 10 one riser below its said cross connection, a casing above said cross connection, the first mentioned riser communicating with one end thereof, the casing having in the bottom of its other end a relatively large aperture, the other riser being 15 of less diameter than said aperture, traversing it and also traversing the top of the casing, the latter closed around it, a tank for liquid fuel in said casing having a valve-controlled faucet positioned to deliver fuel downwardly through the 20 first mentioned riser into the fuel bowl, and the bottom aperture in the casing permitting air circulation therethrough.

2. A device of the character described, comprising a tube having an intermediate part with 25 end risers and having a cross connecting tube from one riser to the other, a fuel burner within one riser below its cross connection, a casing above said cross connection, the first mentioned riser communicating with one end thereof, the 30 casing having a bottom aperture at its other end, the other riser traversing said aperture and traversing the top of the casing, in open and closed relation respectively thereto, a tank for liquid fuel in said casing having a controllable valvular 35 device to deliver downwardly into said fuel burner, and the bottom casing aperture permitting entry of air therethrough around said other riser.

3. A device of the character described, comprising a tube having an intermediate part with 40 end risers and having a cross connecting tube from one riser to the other between their ends, a casing in communication at one end with the top of one riser and having openings in top and bottom of its other end, the other riser traversing the bottom opening in spaced relation and traversing the upper opening in closed relation thereto, and a fuel burner in the lower part of the first 45 mentioned riser having means thereon for spacing it above the bottom of said intermediate part to receive liquid fuel by way of said casing and first mentioned riser.

4. A device of the character described, comprising a tube having an intermediate part with end 50 risers and having a cross connecting tube between said risers, a hollow device communicating with the upper end of one riser and traversed by the other riser, and a fuel burner removably mounted in the first mentioned riser below its communication with said tube, said hollow device 55 having an inlet to the atmosphere spaced from its communication with the first mentioned riser.

5. A heating apparatus, comprising a substantially U-shaped imperforate vertical tube with open inlet and outlet end members and with a 60 medial tubular cross-connecting part between said members constituting substantially a medial coil, and a burner in the inlet end member of the tube below the level of the communication therewith of said cross-connecting part.

6. In a heating apparatus, the combination of 65 an imperforate combustion housing, an inlet pipe communicating with the inside of said combustion housing, an outlet pipe communicating with

the inside of said combustion housing and spaced from said inlet pipe, a cross pipe having one end communicating with the inside of said outlet pipe and its other end communicating with the inside of said inlet pipe at a point above said housing, a removable rod extending into said inlet pipe, a fuel cup burner on said rod and normally positioned below the point where said cross pipe communicates with the inside of said inlet pipe, and a means for dropping fuel oil through said inlet pipe to said fuel cup burner.

7. In a heating apparatus, the combination of 80 an imperforate combustion housing, an inlet pipe communicating with the inside of said combustion housing, an outlet pipe communicating with the inside of said combustion housing and spaced from said inlet pipe, a fuel receiving member at the bottom of said inlet pipe, a means for furnishing fuel to said fuel receiving member, and a cross pipe having one end communicating with the inside of said outlet pipe and its other end communicating with the inside of said inlet pipe at a point above said fuel receiving member.

8. In a heating apparatus, the combination of 85 an imperforate combustion housing, an inlet pipe communicating with the inside of said combustion housing, an outlet pipe communicating with the inside of said combustion housing and spaced from said inlet pipe, a fuel receiving member at the bottom of said inlet pipe, a means for furnishing fuel to said fuel receiving member, and a cross pipe having one end communicating with the inlet pipe at a point above said fuel receiving member and its other end communicating with the outlet pipe at a point higher than the point 95 where the said cross pipe communicates with said inlet pipe.

9. In a heating apparatus, an imperforate pipe having its central portion arranged in convolutions and its two end portions extending upwardly to form an inlet pipe portion and an outlet pipe portion, a means for furnishing fuel oil into said inlet pipe portion, and a cross connecting pipe having one end communicating with the inside of the inlet pipe portion and its other end communicating with the inside of the outlet pipe portion.

10. In a heating apparatus, an imperforate pipe having its center portion convoluted to form a combustion chamber and its two end portions arranged vertically to form inlet and outlet portions, a means for furnishing fuel oil to the inside of said convoluted portion through said inlet pipe portion, and a cross pipe having one end communicating with the inside of said outlet pipe portion and its other end communicating with the inlet pipe portion; said cross pipe having a diameter less than the diameter of said inlet and outlet pipe portions.

11. In a heating apparatus, an imperforate pipe 130 having a central horizontal portion and its two end portions bent upwardly to form inlet and outlet pipe portions, a fuel cup burner inside said inlet pipe portion, a leg on said fuel cup burner for supporting the same a distance from the bottom of said inlet pipe, a means for delivering fuel oil to said fuel cup burner, and a cross pipe having one end communicating with the inside of said outlet pipe portion and its other end communicating with the inside of said inlet pipe portion at a point above said fuel cup burner.

CRENO P. BETTENGA.
